UNITED STATES PATENT OFFICE.

MARION A. ANDREWS, OF YUMA, ARIZONA.

POCKET-BILLIARD TABLE.

1,230,059.

Specification of Letters Patent. Patented June 12, 1917.

Application filed March 4, 1915, Serial No. 12,155. Renewed January 27, 1917. Serial No. 144,996.

To all whom it may concern:

Be it known that I, MARION A. ANDREWS, a citizen of the United States, residing at Yuma, in the county of Yuma, State of Arizona, have invented new and useful Improvements in Pocket-Billiard Tables, of which the following is a specification.

This invention relates to pocket billiard tables in which balls are shot into pockets, and particularly to pocket billiard tables which are provided with runways leading from the pockets to a receptacle for the balls.

The main object of my invention is to provide a pocket billiard table with runways which lead from the pockets to a rack disposed on one end of the table in full view, so that the respective scores of the players may be counted after the finish of a game.

It is another object of my invention to provide a pocket billiard table with runways leading from the pockets to a rack, and a selector mechanism for guiding the balls into any given player's compartment.

It is a still further object of my invention to provide, in a pocket billiard table provided with runways and rack, an electrically operated selector mechanism and an indicator to show which player's rack compartment has been selected, and thereby to indicate the player who is to shoot next.

I attain these objects by the mechanism illustrated in the accompanying drawing, in which:

Figure 1 is a plan view of a table provided with my improved runway and rack construction, with parts broken away to more clearly show the runway and switch.

Fig. 2 is a partial vertical section through the rack and runway.

Fig. 3 is a view of the solenoid and operating means for the selector mechanism viewed from underneath the table.

Fig. 4 is a wiring diagram showing the electrical circuits for the selector operating mechanism and indicator.

More specifically, 5 designates a pocket billiard table provided with the usual cushion rails 6, 7, 8 and 9, and provided with pockets 10, 11, 12, 13, 14 and 15. Each of the pockets is open at its lower end so that a ball shot into the pocket may pass through and upon a runway connected to the pocket.

Mounted on one end of the table and partially exposed to view is a rack 16 having

rack runways 17, 18, 19, 20, 21 and 22 with the sides of the runways disposed parallel to the end of the table, so that the balls will lie in horizontal rows therein. Connected at right angles to the rack runways 17, 18, 19, 20, 21, and 22 are runways 23, 24, 25, 26, 27 and 28. Leading from pocket 12 is a runway 29 which discharges upon a trough plate 30 and has a gentle incline which gives the ball sufficient speed in its drop, but does not cause too rapid movement. Leading from the pocket 13 is a runway 31 also connected to trough plate 30; runway 31 being similar to 29.

Connected to the pocket 11 is a runway 32 which is spiral in form in order to give a gentle incline to the runway since the difference in level between pocket 11 and trough plate 30 is too great for a straight trough. The spiral increases the length of the trough, thereby providing a gentle grade.

Leading from pocket 14 is a runway 33, which is similar in shape to runway 32. From end pocket 10, a runway 34 is connected to the spiral 35, and from end pocket 15 a similar runway 36 is connected to the spiral runway 37. Spiral runways 35 and 37 are connected to a common runway 38 into which the balls are discharged. Balls passing along runways 29 and 31 are also guided by means of plate 30 into common runway 38.

Pivottally connected at the end of common runway 38 is a switch runway 39, which can be adjusted to discharge the billiard balls into any one of the runways 23, 24, 25, 26, 27 and 28. The rack runways 17, 18, 19, 20, 21 and 22 have apertures 40, 41, 42, 43, 44 and 45 respectively, large enough for a billiard ball to pass through. These apertures are closed by a slide 46. Disposed below the rack 16 is a drawer 47 having a triangle to receive the balls, and which serves as a carrier.

My preferred selector mechanism comprises a lever 48 pivoted at one end 49 to trough 30, and having at the free end a slot within which is disposed a pin 50. Pin 50 is secured to the runway switch 39. Mounted adjacent to the center of lever 48 is a pin 51 which is engaged by a cam 52. Cam 52 is designed to coöperate with pin 51 and in its movement connect the runway switch successively with troughs 26, 27, 28, 25, 24 and 23. A spring 53 tends to move

the runway switch to a position connecting it with runway 26, and the cam 52 is so designed that after the runway switch 39 is connected with runway 23, the next movement of the cam will allow the spring 53 to return the switch 39 to trough 26.

Cam 52 is fixedly mounted upon a pin carrying a ratchet wheel 54, whose teeth are engaged by a pawl 55 mounted upon a lever 56. Spring 57 is connected to lever 56 and the pawl 55 and holds the pawl in engagement with the ratchet wheel 54. Lever 56 is pivoted at one end 58 and guided at the free end by a bar 59 secured to plate 30 by brackets 61 and 62. A solenoid armature 63 is pivotally connected to the lever 56 by pin 64 and is mounted within solenoid 65. A spiral spring 66 abuts the lever 56 and solenoid 65, thus tending to force the armature out of the solenoid.

A wiring system is provided for the solenoid which, as shown diagrammatically in Fig. 4, comprises a source of electrical energy 67, which is here shown as a battery of cells, but may be any other device such as an electric generator or a power circuit.

Connected in series with solenoid 65 is an indicator 68 to indicate the rack runway with which switch 39 is connected. In series with the source of electrical energy 67, indicator 68 and solenoid 65 are a plurality of electrical switches 69, 70, 71 and 72, which are in parallel, and disposed so that the closure of any one of the switches will close the electrical circuit and allow the solenoid and indicator to be energized. Switches 69, 70, 71 and 72 are preferably push buttons, as indicated by 73, but may be any other type of electrical switch, and one switch may be disposed upon each side of the billiard table.

My runway switch 39 may be operated manually if desired by means of an operating bar 74 pivoted on the table at 75 and extending through to the opposite ends of the table. Depending from bar 74 is a link rod 77 which may be engaged in aperture 77' with switch 39. The ends of the bar 74 pass through slots in the ends of the table close to the rail. The slots are notched so that the bar may be engaged with a notch, and in such position the switch is connected to the desired runway.

In the operation of my preferred construction, the balls as they are shot into the pockets pass down the runways and are guided by the runway switch into a rack runway which has been selected, thus if the switch is positioned to guide the balls into runway 26, they will pass out into the player's compartment 20 in full view of the players. After the player has finished his shot, the next player presses any push button on the side, the solenoid 65 being energized thereby and retracting the armature

63, pulling with it the lever 56 and moving the ratchet wheel 54, pawl 55 engaging it, thereby moving cam 52 and forcing lever 48 over to connect the switch 39 with the next runway 27. As each player steps up for his shot he presses a button and in this way the switch registers successively with each of the runway troughs 26, 27, 28, 25, 24 and 23, and after the last player shoots, the switch 39 on the next closure of the circuit by pressing a button is moved by the spring back to the runway 26.

After the completion of the game, the balls are counted in the rack 16, being exposed to view, slide 46 is then moved to uncover the apertures 17, 18, 19, 20, 21 and 22, thereby permitting the balls to drop into the triangle in the receptacle 47. Receptacle 47 is then removed to top of table, the triangle with the balls therein positioned on the table, the triangle removed therefrom, and a new game started.

What I claim is:

1. The combination with a pocket billiard table having ball pockets, of a rack disposed at one end of and extending beyond the table sufficient to expose all of the balls therein to view, horizontal ball display runways in the exposed portion of said rack, runways leading from said pockets, a selector mechanism connecting said runways and said rack, discharge means for said rack, and a carrier drawer slidingly mounted below and upon said rack.

2. The combination with a pocket billiard table having ball pockets, of a rack disposed at one end of and extending beyond the table sufficient to expose all of the balls therein to view, horizontal ball display runways in the exposed portion of said rack, runways leading from said pockets, a selector mechanism connecting said runways and said rack, discharge means mounted on said rack, a ball receptacle detachably mounted on said rack to receive said balls, and means for controlling the passage of balls into said receptacle.

3. The combination with a pocket billiard table having ball pockets, of runways leading from said pockets to a common runway, a ball rack provided with independent runways mounted on said table, a swinging runway for progressively connecting the common runway with the independent runways, a cam mechanism for moving said swinging runway, and an intermittent grip device for moving said cam mechanism.

4. The combination with a pocket billiard table having ball pockets, of runways leading from said pockets to a common runway, a ball rack provided with independent runways mounted on said table, a swinging runway for progressively connecting the common runway with the independent runways, a cam follower operatively secured to

said swinging runway, a cam for moving said cam follower, and an intermittent grip device for moving said cam.

30

5. The combination with a pocket billiard table having ball pockets, of runways leading from said pockets to a common runway, a ball rack provided with independent runways mounted on said table, a swinging runway for progressively connecting the common runway with the independent runways, a lever operatively secured to said swinging runway, a cam follower mounted upon said lever, a cam for moving said cam follower, and an intermittent grip device for 10 moving said cam.

6. The combination with a pocket billiard table having ball pockets, of runways leading from said pockets to a common runway, a ball rack provided with independent runways mounted on said table, a swinging runway for progressively connecting the common runway with the independent runways, a lever pivoted to said table and secured to said swinging runway, a cam follower on said lever, a cam engaged with said cam follower, a ratchet wheel secured to said cam, an operating lever pivoted on said table, a pawl mounted on said operating lever and engaged with said ratchet wheel, and a spring secured to the table and the first named lever for retracting the latter.

45

In witness that I claim the foregoing I have hereunto subscribed my name this 23rd day of February, 1915.

MARION A. ANDREWS.
